(57) **CLAIM**

The ornamental design for a harness belt, as shown and described.

DESCRIPTION

FIG. 1 is a perspective view of the design, the belt shown connected;

FIG. 2 is a top plan view thereof, the belt shown unconnected;

FIG. 3 is a front view thereof;

FIG. 4 is a bottom view thereof; and,

FIG. 5 is a rear view thereof.

Portions of the belt are shown broken away to indicate indeterminate length.

Where included, broken lines showing environment or structure are for illustrative purposes only and form no part of the claimed design.
